CENTRALIZED TRAFFIC CONTROL SYSTEM
FOR RAILROADS FOR THE CODE CONTROL
OF INTERLOCKED TRACK SWITCHES AND
SIGNALSEarl M. Allen, Swissvale, Pa., assignor to The
Union Switch & Signal Company, Swissvale,
Pa., a corporation of Pennsylvania

Application June 11, 1945, Serial No. 598,695

7 Claims. (Cl. 246—134)

1

My invention relates to centralized traffic control systems for railways, and more particularly to railway traffic controlling apparatus for the remote control of a track layout including electrically interlocked track switches and railway signals.

In systems of this character, it is customary to provide a control board or panel upon which the switch and signal control levers are mounted, and associated therewith, an illuminated track diagram representing the track layout and containing red lamps which are lighted to indicate train movements through the various track sections. Heretofore the usual practice has been to also provide a group of lamps for each switch or signal lever, one lamp of each group being normally lighted to indicate the position of the switch or the condition of the signal controlled by the associated lever. If the plant is a large one this involves the continuous display of such a large number of lights as to tend to confuse the operator, requiring careful observation in order to correctly set up the different routes.

One object of my invention is the provision of an improved control board for a system of this character, in which all of the lever lamps as well as those for illuminating the track diagram are normally dark. The manipulations involved in setting up routes are thereby facilitated, because the only lamps lighted at any one time are those which are directly of interest to the operator.

In the embodiment of my invention disclosed herein I provide a single red lamp for each lever, which becomes lighted when the lever is moved to a new position, and which becomes dark again when the switch or signal which the lever controls assumes a corresponding position. In accordance with one feature of my invention I provide a lamp on the track diagram for the exit end of each route by means of which a directional indicator or arrow is illuminated to mark the destination of each established route, and I also provide a green lamp at each signal location on the track diagram which is lighted when the corresponding signal is cleared. In accordance with this plan, when the operator reverses a signal lever for clearing a signal governing traffic movements over a selected route, a red lamp above the lever becomes lighted, and when a route governed by such signal is established which corresponds with the positions of the switch levers, the lamps associated with these switch levers become dark, and on the track diagram, the corresponding exit lamp becomes lighted, thereby distinctively indicating the des-

2

mination of the selected route by the lighting of only one lamp. Furthermore, in order to permit the operator to verify the selection before the signal is cleared, the operations for clearing the signal are divided into two steps. The operator first reverses the signal lever for the signal at the entrance end of the route and then, after verifying the destination as indicated by the exit lamp, presses a starting button associated with the lever to effect the clearing of the signal. When the signal clears, the red lamp associated with the lever is extinguished and a green lamp on the track diagram at the signal location becomes lighted.

In the form shown herein, the apparatus of my invention is so arranged that all communication between the control office and the plant location is effected over a single pair of line wires, employing a selective code system such as that shown in Letters Patent of the United States No. 2,229,249, issued January 21, 1941, to Lloyd V. Lewis for Remote Control Systems.

I shall now describe one form of apparatus embodying my invention and shall then point out the novel features thereof in claims.

Referring to the accompanying drawings, Figs. 1A to 1E, inclusive, taken together show the circuits and apparatus located at the office for one form of my invention as applied to a typical track layout, while Figs. 2A to 2D, inclusive, show the corresponding wayside apparatus at the plant location.

For simplicity, a layout of a minimum size has been chosen to illustrate the invention, and as shown by the track plan in Fig. 2A, this comprises a track section 1T containing a single switch 1 and extending between the opposing signals 2RA or 2RB and 2LA or 2LC, which section is connected by a crossover 3 with a section 3T located in a parallel track and extending between the opposing signals 4RA or 4RC and 4L.

Considering the drawings in detail, Fig. 1A shows the operator's control board, which includes an illuminated track diagram of the layout mounted above a panel containing the usual switch and signal control levers, while Fig. 1B shows the circuits for the track diagram lamps. Fig. 1C shows the office indication relays for controlling the circuits of Fig. 1B, which relays are controlled by indication codes transmitted in response to changes in the condition of the controlling relays in the field. In order to make it unnecessary to consider herein the details of operation of the code system, the various intermittently available indication channels which it provides are represented as individual wires, num-

bered 109 to 115, inclusive, to correspond with the wires of Patent No. 2,229,249, over which the code impulses are supplied to the relays whenever a delivery relay such as relay 2D or 4D is momentarily energized. For simplicity these wires are indicated herein as extending directly to the contacts of the controlling relays of Figs. 2A to 2D. The indication relays as shown differ from those of the remote control system of the Lewis patent hereinbefore referred to, and correspond to those employed in a modification of that system which is particularly adapted for use in connection with the apparatus of my invention and which is shown in Letters Patent of the United States No. 2,442,603, issued June 1, 1948, to A. P. Jackel. In this arrangement but one signal indication relay such as relay 2GK is provided for indicating the clearing of any one of the conflicting or opposing signals of the group of signals identified by the same number, and a second relay such as relay 2ASK is provided to indicate the transmission of a control code for clearing any of the signals of the corresponding group and to also indicate the release of any of the approach locking relays associated with such group of signals.

Fig. 1D shows a route circuit network for controlling route relays such as the relay 2RGS of which one is provided for each of the two reverse positions of the associated signal lever such as the lever 2SG, the route circuits for these relays including contacts of the switch levers such as lever 1SW and of the switch indication relays and conforming to the various routes. Each route relay such as the relay 2RGS controls the circuit in Fig. 1B for a green lamp 2RBE or 2RAE for the corresponding signal and for the exit lamp 2LX or 4LX at the opposite end of the established route, and in Fig. 1C, locally controls the associated lock indication relay 2ASK.

Fig. 1E shows the circuits for the lever lamps and for governing the transmission of the control codes by which the switches and signals are controlled in accordance with the positions of the control levers. For an understanding of my invention it is deemed sufficient to point out that a control code is initiated by energizing a starting relay such as the relay 1ST or 3ST which governs the transmission of a group of code elements for selecting the group of devices in the field which the associated levers controls and also energizes a selector relay 1S or 3S by means of which one or more of a group of wires 101-105 corresponding to the similarly numbered control code channels of Patent No. 2,229,249 are energized in accordance with the positions of the levers. As shown herein, the circuits of the patent are modified in two particulars; first, the circuits for energizing wire 102 or 104 by reversal of a signal lever such as 2SG include contacts of the associated route relays of Fig. 1D, so that a code including elements for clearing a signal cannot be transmitted until the route governed by the signal is established and the route relay is energized, and second, the switch levers such as lever 1SW are made of the push-turn type and are provided with an auxiliary contact *a* which is closed to energize the associated starting relay whenever the lever is rotated from one of its two operating positions to the other, but without operating the usual starting button such as the button 2STB by which a code is initiated following an operation of the signal lever 2SG.

Fig. 2A in addition to the track plan shows the circuits for the track relays TR, for the ap-

proach relays 4RAR and 2LAR, for the switch locking relays LR, a section locking relay 1WS, and for the switch operating relays WR and the associated switch repeating relays NWP and RWP.

Fig. 2B shows the circuits for the code controlled switch and signal control relays NWS, RWS, LHS, RHS and COS, which correspond to those of Patent No. 2,229,249 except that for simplicity the circuits are represented as providing direct connections over wires 101-105 to those of Fig. 1E when a delivery relay 1D or 3D is momentarily energized along with relay 1S or 3S, in response to a control code.

Fig. 2C shows the signal circuits, comprising a circuit network conforming to the track layout, for controlling the mechanisms for the various signals shown in Fig. 2A. Each mechanism is identified by the reference character G preceded by the designation for the corresponding signal as shown in the track plan, it being understood that these are of the well-known searchlight type.

Each signal mechanism comprises a normally lighted lamp and a winding which when energized opens a contact, shown in Fig. 2D, and also operates a spectacle frame for placing different colored roundels in front of the lamp. Each signal is adapted to display a red or stop aspect when deenergized, to display a yellow or caution aspect when energized, provided terminal B is connected to the right-hand terminal of its winding and to display a green or proceed aspect when energized with terminal B connected to the left-hand terminal of its winding. The high speed signals 4RA and 2LA are the only ones shown which provide the third aspect, their indications changing from caution to proceed when a line relay 4RD or 2LD becomes energized. It is to be understood that relay 4RD or 2LD is energized when the next signal in advance for the same direction, not shown herein, indicates caution or proceed.

Fig. 2D shows the circuits for approach locking relays LAS and RAS which are controlled by the signals and by their control relays in the conventional manner. These relays control the switch locking relays LR of Fig. 2A, which relays must be energized to permit operation of the track switches, and as shown by Fig. 2C, the approach locking relay LAS or RAS for a signal that is to be cleared as well as the switch locking relays LR controlled thereby must occupy their deenergized positions in order to permit the signal to be cleared. As shown in Fig. 2D, the approach locking relay LAS or RAS is released by the operation of the code controlled signal control relay RHS or LHS, but the control of the latter by the route relay RGS or LGS of Fig. 1D is such as to insure that the switches of a route being set up will not become locked until all have assumed the required positions.

Similar reference characters refer to similar parts in each of the several views.

To simplify the circuits, I have herein shown only the terminals of the sources of current for energizing the relays, the reference character B designating the positive or supply terminal and the reference character C the negative of common return terminal of the local sources of current at the office and field location, respectively.

The operation of the system of my invention will now be described under different assumed conditions, starting with the apparatus in its normal condition as shown, in which all of the

indication lamps in Fig. 1A are dark, and assuming first that the operator desires to set up the route which includes switch 1 reversed and crossover 3 reversed and to clear signal 2RB for a movement from left to right over that route.

The operator first moves levers 1SW and 3SW to their reverse or right-hand positions, thereby closing the lever contacts *a* in Fig. 1E momentarily to pick up relays 1ST and 3ST, and lighting the lamps 1WE and 3WE over the circuits including the switch lever contacts *b* and back contacts *f* of the reverse indication relays 1RWK and 3RWK.

The circuits for the route relays of Fig. 1D are now open. The circuit from contact *b* of lever 2SG to contact *c* of the same lever is open at contact *d* of lever 1SW and at contact *d* of lever 3SW; the circuit from contact *b* of lever 4SG to contact *c* of the same lever is open at contact *e* of lever 3SW, and the circuit from contact *b* of lever 2SG to contact *c* of lever 4SG is open at contact *e* of relay 1RWK and also at contact *c* of relay 3RWK, consequently these route relays are released and wires 102 or 104 are not energized, and the two control codes which are now transmitted in response to the operation of the starting relays 1ST and 3ST include no elements for clearing any signal. Wire 103 is energized over the reverse contact *a* of lever 1SW or 3SW, so that in Fig. 2B the switch control relay 1RWS becomes energized and relay 1NWS releases in response to the first control code, and relay 3RWS is energized and relay 3NWS released in response to the second, thereby reversing the switch operating relays 1WR and 3WR, Fig. 2A, to release the switch normal indicating relays 1NWP and 3NWP and to supply energy to the switch machines 1SM, 3SM and 3ASM to operate the track switches to reverse. The release of relays 1NWP and 3NWP initiates the transmission of indication codes in the usual manner, whereby relays 1NWK and 3NWK are released, which prevents the extinguishing of lamp 1WE or 3WE or the re-establishment of the original route circuits in case the operator should inadvertently restore lever 1SW or lever 3SW to its former position.

When the track switches become locked reverse, relays 1RWP and 3RWP become energized and initiate the transmission of indication codes whereby relays 1RWK and 3RWK are energized to extinguish lamps 1WE and 3WE, and to prepare a route circuit in Fig. 1D over the closed contacts of the switch levers. Noting that the switch lever lamps have become dark, the operator moves lever 2SG to its right-hand reverse position, completing a pick-up circuit for the route relay 2RGS. This circuit may be traced in Fig. 1D from terminal B at back contact *b* of relay 4LGS over the normal contact *c* of lever 4SG, the reverse contact *e* of lever 3SW, contact *c* of relay 3RWK, contact *e* of relay 1RWK, the reverse contact *d* of lever 1SW, the right-hand contact *b* of lever 2SG, back contact *b* of relays 1ST and 2ASK through relay 2RGS to terminal C. In response to the operation of lever 2SG, lamp 2NE becomes lighted, its circuit as shown in Fig. 1E extending from terminal B at back contact *e* of relay 2ASK, back contact *f* of relay 2RGS and the right-hand contact *d* of lever 2SG through lamp 2NE to terminal C. Relay 2RGS now assumes its energized position and its contact *f* shifts the circuit for lamp 2NE to the branch which extends to terminal B at back contact *c* of relay 2GK. The exit lamp 4LX becomes lighted, its circuit, shown in Fig. 1B, extending

from terminal B at front contact *c* of relay 2RGS over contact *c* of relay 1RWK, contact *b* of relay 3RWK and back contact *c* of relay 4LGS through lamp 4LX to terminal C.

After observing the lighting of lamps 2NE and 4LX, and thereby checking that the desired route is established, the operator presses the starting button 2STB momentarily to energize the starting relay 1ST. In Fig. 1D, contact *b* of relay 1ST shifts to its upper position and thereby inserts contact *a* of relay 2RGS into the route circuit over which relay 2RGS is energized. It follows that relay 2RGS must assume its energized position prior to the operation of relay 1ST, and cannot become energized while a code is in progress with relay 1ST energized, for example. The energization of relay 1ST, following that of relay 2RGS, initiates the transmission of a control code, during which relays 1S and 1D pick up to effect the energization of wire 104, over contact *b* of relay 1S, right-hand contact *a* of lever 2SG and contact *g* of relay 2RGS, and wire 103 is also energized as in the preceding code, over contacts *a* of relay 1S and lever 1SW, so that, in Fig. 2B, relay 2RHS becomes energized and relay 1RWS is held energized. The energization of relay 1S also completes a circuit in Fig. 1C from terminal B at a contact *c* of the code system relay OM, which contact is closed only during the transmission of a control code, over contacts *e* of relays 2RGS and 1S and a back contact of relay 2D through the winding of the lock indication relay 2ASK to terminal C, so that relay 2ASK picks up and completes a stick circuit at its own front contact *a* and in Fig. 1D, contact *b* of relay 2ASK shifts to its upper position to disconnect relay 2RGS from the route circuit and to hold it energized over a stick circuit including its own front contact *b*. The transmission of a control code for clearing the signal thus locks relay 2RGS energized and thereby prevents the energization of the route relays for opposing or conflicting routes, the circuits for which include its back contact *b*.

When the signal control relay 2RHS becomes energized in response to this code, its back contact *e* opens in Fig. 2D and releases the approach locking relay 2RAS, and in Fig. 2A, contact *c* of relay 2RAS opens, releasing the switch locking relays 1LR and 3LR, and the latter relays then open their contacts *a* and *b* to isolate the switch control relays 1WR and 3WR and thereby lock the track switches in the positions required for the route, and also open their contacts *e*, *f* and *g*, in Fig. 2B, to prevent a change in the positions of the switch control relays as long as the switches remain locked.

In Fig. 2C, a circuit for the signal mechanism 2RBG which corresponds to the established route has been prepared by the closing of contacts *a* and *b* of relay 1RWP, contact *a* of relay 3RWP, contacts *c* and *d* of relay 2RHS, and the back contact *d* of relay 2RAS. This circuit extends to terminal B at front contact *d* of relay 4LAS and is completed by the closing of back contacts *c* of relays 1LR and 3LR, so that mechanism 2RBG becomes energized to clear signal 2RB of Fig. 2A.

The release of relay 2RAS and the consequent energization of mechanism 2RBG as described results in the initiation of an indication code, causing relay 2D, Fig. 1C to be momentarily energized, completing circuits over wires 112 and 115 to hold the indication relays 2ASK and 1RWK energized, and also completing a circuit

controlled by contact *a* of mechanism 2RBG including wire 114 to cause the signal indication relay 2GK to become energized.

In Fig. 1E, the red lamp 2NE is extinguished by the opening of back contact *c* of relay 2GK and the green lamp 2RBE in the track diagram becomes lighted due to the closing of its circuit in Fig. 1B which extends from terminal B at contact *b* of relay 2GK over contacts *d* of relays 2RGS and 1RWK through lamp 2RBE to terminal C.

The established route is thus indicated on the track diagram by the lighting of the green lamp 2RBE at one end and by the exit lamp 4LX at the other end, all other indication lamps being dark.

I shall now assume that a train governed by signal 2RB passes through section 1T. The track relay 1TR will release, initiating an indication code by which relay 1TK, Fig. 1C, is energized, closing a circuit in Fig. 1B to light a red lamp 1TE in the track diagram. The operator will then restore lever 2SG to its normal center position and press the starting button 2STB, thereby initiating a control code which releases relay 2RHS, thereby deenergizing mechanism 2RBG and restoring signal 2RB to stop. The red lamp 2NE becomes lighted over the center contact *d* of lever 2SG and the front contact *d* of relay 2GK, lamps 2RBE and 4LX in the track diagram remaining lighted. If this control code is received while section 1T is occupied, relay 2RAS, Fig. 2D, becomes reenergized over the circuit including back contact *a* of relay 1TR, and the resulting indication code will cause relays 2GK and 2ASK to release. Relay 2ASK will release relay 2RGS and lamps 2NE, 2RBE and 4LX will be extinguished. On the other hand, if signal 2RB is put to stop by a control code received while section 1T is not occupied, relay 2RAS will remain released, and an indication code will be initiated by the release of mechanism 2RBG by which relay 2GK is released, relays 2ASK and 2RGS remaining energized. Lamp 2RBE will be extinguished, lamp 4LX will remain lighted, and lamp 2NE will display a flashing indication, being energized intermittently over back contact *d* of relay 2GK and front contact *d* of relay 2ASK from one terminal FB of a suitable source of interrupted current. In Fig. 2D, the release of relay 2RHS when section 1T is unoccupied completes a circuit over back contact *a* of relay 2RAS and front contact *d* of relay 1TR for a time element relay 1TER, which relay becomes energized and opens its checking contact *c* in the signal circuits of Fig. 2C and after a suitable time interval completes a circuit at its contact *a*, in Fig. 2D, to reenergize relay 2RAS, whereupon an indication code is initiated whereby relays 2ASK and 2RGS are released in turn, and lamps 2NE and 4LX are extinguished. It will be seen therefore that the flashing of lamp 2NE provides a distinctive indication which persists as long as the time locking by relays 1TER and 2RAS is effective. This flashing indication is also displayed automatically under the condition that the signals controlled by lever 2SG have not been cleared, in the event that relay 2RAS or 2LAS releases due to a fault, relay 2ASK becoming energized and completing a flashing circuit for lamp 2NE over back contact *f* of relay 2LGS or 2RGS and front contact *e* of relay 2ASK, or over back contact *d* of relay 2GK and front contact *d* of relay 2ASK whereby lamp 2NE is

caused to flash irrespective of the position of lever 2SG.

I shall now assume that the route from signal 2RB to signal 4L is set up as above described, with relays 2ASK and 2RGS released and the indication lamps dark, and that the operator moves lever 4SG to its left-hand reverse position to clear signal 4L. The operations occurring as the result of pressing the starting button 4STB in this case are analogous to those already described, the principal difference being in the switch locking. Since relay 4LAS may be reenergized as soon as a train passes signal 4L and occupies the first section 3T of the route, and since relay 1TR does not release until the train enters the second section 1T of the route, neither of these relays is adapted to lock switch 1 when a train in section 3T is approaching section 1T. To maintain switch 1 locked under this condition a section lockin grelay 1WS is provided, the operation of which will be self evident from the circuits as shown in Fig. 2A.

I shall next assume that the apparatus has been restored to the condition shown, with switches 1 and 3 normal, and that the operator wishes to clear the high signal 2LA for a train movement over the upper main track. The operator will first move lever 2SG to the left, lighting lamp 2NE. The route relay 2LGS becomes energized at once over the route circuit already established, lighting lamp 2RAE, whereupon the operator presses button 2STB to energize the starting relay 1ST and initiate the transmission of a control code by which relay 2ASK, in Fig. 1C, is energized over contact *e* of relay 2LGS, and relay 2LHS, in Fig. 2B, is energized over wire 102. Relays 2LAS, 1LR and 3LR release to lock the track switches and to complete a circuit for mechanism 2LAG to clear signal 2LA, following which an indication code is transmitted to energize relay 2GK and thereby extinguish lamp 2NE and to light lamp 2LE in the track diagram. The approach of a train is indicated by the lighting of lamp 2AE, and when the train passes signal 2LA at clear, mechanism 2LAG is released to put the signal automatically to stop by the opening of contact *c* of the track relay 1TR in its circuit, and at the same time relay 2LHS, Fig. 2B, is released by the opening of contact *f* of relay 1TR, and relay 2LAS, in Fig. 2D, is reenergized automatically over the circuit including back contact *b* of relay 1TR. The indication code which is initiated in this case causes relay 1TK to become energized to light lamp 1TE, and relays 2GK and 2ASK to release, thereby releasing relay 2LGS and causing lamps 2LE and 2RAE to become dark, and lamp 2NE becomes steadily lighted over the left-hand contact *d* of lever 2SG, back contact *f* of relay 2LGS and back contact *e* of relay 2ASK, becoming dark when lever 2SG is returned to its normal center position to correspond with the condition of the signal, the transmission of a stop signal control code not being required in this instance.

In the event signal 2LA is restored manually to stop with the approach section 2LT unoccupied so that the approach relay 2LAR, Fig. 2A, is energized, relay 2LAS becomes energized at once in response to the release of relay 2LHS and mechanism 2LAG, over front contact *b* of relay 2LAR, but if the approach section 2LT is occupied at the time, relay 2LAS is reenergized only after the time interval imposed by relay 1TER.

It will be noted that the approach relay 2LAR is a stick relay which can be picked up only when

the front contact b of relay 2LAS is closed. This arrangement insures that if signal 2LA is put to stop when an approaching train occupies section 2LT, relay 2RAR will be held released by relay 2RAS, and consequently relay 2LAS remains released to maintain the switch locking effective even though the track relay 2LTR is temporarily energized due to ineffective shunting of the track rails by the approaching train.

Associated with the high speed signal 2LA or 4RA, a slow speed or "call on" signal 2LC or 4RC is provided, which may be controlled in the manner described in Patent No. 2,229,249 by relay 2COS or 4COS in response to the operation of a key 2CO or 4CO associated with the signal lever.

It will be understood that the several control codes which are transmitted when a plurality of starting relays ST are operated, are transmitted in a prescribed order of code superiority. The operation of the apparatus of my invention is such that if any of the codes of a group includes elements effective to change the position of a track switch none of these codes will include an element for clearing a signal governing movements over that switch, due to the release of the route relays of Fig. 1D by switch lever operation. On the other hand, if a code for clearing a signal is transmitted first, the resultant locking of the switches is anticipated by the locking of the route relay in its energized position as soon as the code is transmitted, and one effect of this code is to release certain locking relays whereby codes transmitted subsequently are rendered incapable of changing the positions of the switch control relays.

Although I have herein shown and described only one form of apparatus embodying my invention, it will be understood that various changes and modifications may be made therein within the scope of the appended claims without departing from the spirit and scope of my invention.

Having thus described my invention, what I claim is:

1. In a centralized traffic control system for railroads, a track layout including track switches and signals for governing traffic movements over the different routes in said layout, a miniature track diagram of said layout at a control office, switch levers for controlling said switches, route relays for governing said signals, signal levers for controlling said route relays to effect the clearing of said signals, switch indication relays which reflect the positions of said switches and signal indication relays which reflect the condition of said signals, a route circuit network including a circuit for each route relay closed when the associated signal lever is reversed but only if said switch indication relays indicate that a route corresponding to the positions of said switch levers is set up which has its entrance end at the location of the signal which such route relay governs, a signal lamp at each signal location in said track diagram, an exit lamp at the exit end of each route in said track diagram, a circuit for each exit lamp prepared by said switch indication relays when a route having the corresponding exit end is set up and completed upon the energization of the route relay for the signal at the entrance end of such route over the corresponding circuit in said network, and a circuit for the signal lamp for said signal prepared by said route relay and completed by the corresponding signal indication relay when said signal clears.

2. In a centralized traffic control system for railroads, a track layout including track switches and signals for governing traffic movements over the different routes in said layout, a miniature track diagram of said layout at a control office, switch levers for controlling said switches, route relays for governing said signals, signal levers for controlling said route relays to effect the clearing of said signals, switch indication relays which reflect the positions of said switches, signal indication relays which reflect the condition of said signals, a route circuit network including a circuit for each route relay closed when the associated signal lever is reversed but only if said switch indication relays indicate that a route corresponding to the positions of said switch levers is set up which has its entrance end at the location of the signal which such route relay governs, a signal lamp at each signal location in said track diagram, an exit lamp at the exit end of each route in said track diagram, a circuit for each exit lamp prepared by said switch indication relays when a route having the corresponding exit end is set up and completed upon the energization of the route relay for the signal at the entrance end of such route over the corresponding circuit in said network, a push button associated with each signal lever, a signal control relay for each signal, means responsive to the operation of each push button having its associated signal lever reversed for operating the signal control relay for the associated signal, the operation of such signal control relay being also dependent upon the energization of the associated route relay as manifested by the lighting of an exit lamp on said track diagram, locking means controlled by each energized route relay in response to the operation of the associated push button for maintaining such route relay energized as long as the associated signal lever is reversed irrespective of the condition of the circuit in said network over which such route relay was initially energized, means for clearing each signal in response to the energization of the corresponding signal control relay, and means controlled by the signal indication relay for the signal that is cleared and by the energized route relay for selectively lighting the signal lamp on the track diagram which corresponds to the signal that is cleared whereby the route set up is indicated by the lighting of a signal lamp at one end and of an exit lamp at the other end of its representation on the track diagram.

3. In a centralized traffic control system for railroads, a track layout including track switches and signals for governing traffic movements over the different routes in said layout, a miniature track diagram of said layout at a control office, switch levers for controlling said switches, route relays for governing said signals, signal levers for controlling said route relays to effect the clearing of said signals, switch indication relays which reflect the positions of said switches, a route circuit network including a circuit for each route relay closed when the associated signal lever is reversed but only if said switch indication relays indicate that a route corresponding to the positions of said switch levers is set up which has its entrance end at the location of the signal which such route relay governs, an exit lamp at the exit end of each route in said track diagram, a circuit for each exit lamp closed only when the route relay for a signal at the opposite end of the layout from the location designated by such exit lamps is energized over a circuit in said

network completed by said switch indication relays which indicates that a route is set up from the location of such signal to the location designated by said exit lamp, whereby the establishment of each route is indicated by the lighting of a lamp which also indicates its destination on said track diagram, and a circuit for clearing each signal including a normally open manually controllable contact and a reverse contact of its signal lever and also including a contact closed in response to the energization of its route relay as manifested by the lighting of the corresponding exit lamp, whereby the destination of such route may be verified before the signal is cleared, by observation of said exit lamp.

4. In a centralized traffic control system for railroads, a track layout including track switches and signals for governing traffic movements over the different routes in said layout, a miniature track diagram of said layout at a control office, switch levers for controlling said switches, route relays for governing said signals, signal levers for controlling said route relays to effect the clearing of said signals, switch indication relays which reflect the positions of said switches, a route circuit network including a circuit for each route relay closed when the associated signal lever is reversed but only if said switch indication relays indicate that a route corresponding to the positions of said switch levers is set up which has its entrance end at the location of the signal which such route relay governs, an exit lamp at the exit end of each route in said track diagram, a circuit for each exit lamp closed only when the route relay for a signal at the opposite end of the layout from the location designated by such exit lamp is energized over a circuit in said network completed by said switch indication relays which indicates that a route is set up from the location of such signal to the location designated by said exit lamp, and auxiliary manually operable means associated with each signal lever for effecting the clearing of the signal which the route relay associated with said lever controls, so arranged that the clearing of any signal in response to the energization of its route relay is prevented unless said auxiliary means is manually operated after the destination of the route which such signal governs has been indicated on the track diagram by the lighting of the corresponding exit lamp.

5. In a centralized traffic control system for railroads, a track layout including track switches and signals for governing traffic movements over the different routes in said layout, a miniature track diagram of said layout at a control office, switch levers for controlling said switches, route relays for governing said signals, signal levers for controlling said route relays to effect the clearing of said signals, switch indication relays which reflect the positions of said switches, a route circuit network including a circuit for each route relay closed when the associated signal lever is reversed but only if said switch indication relays indicate that a route corresponding to the positions of said switch levers is set up which has its entrance end at the location of the signal which such route relay governs, an exit lamp at the exit end of each route in said track diagram, a circuit for each exit lamp closed only when the route relay for a signal at the opposite end of the layout from the location designated by such exit lamp is energized over a circuit in said network completed by said switch indication relays which indicates that a route is set up from

the location of such signal to the location designated by said exit lamp, a push button associated with each signal lever, signal clearing means responsive to the operation of each push button having its associated signal lever reversed for clearing the associated signal, said signal clearing means being effective to clear its signal only if operated at a time when the associated route relay is energized as manifested by the lighting of the exit lamp for a route governed by such signal.

6. In combination with a railway track layout including a power operated track switch, a signal for governing traffic movements over a route which includes the switch, a signal lever operable between normal and reverse positions for controlling said signal, a route relay which is energized in response to the reversal of said lever provided the track switch occupies the position required for said route, a circuit for clearing said signal including a contact closed by the route relay in its energized position and a contact closed by said lever in its reverse position, an indication relay controlled by said signal, an indication lamp associated with said lever, a first circuit for energizing said indication lamp including a contact closed by said indication relay when the signal is cleared and a contact closed by said signal lever in its normal position, a second circuit for energizing said indication lamp including a contact closed by said indication relay when the signal is at stop, and a contact closed by the signal lever in its reverse position, said second circuit also including a contact closed by the route relay in its energized position, and a third circuit for energizing said indication including said contact closed by the signal lever in its reverse position and a contact closed by said route relay in its released position.

7. In a centralized traffic control system for railroads, a track layout including track switches and signals for governing traffic movements over the different routes in said layout, a track diagram representing said track layout having an exit lamp thereon for the exit end of each route, route relays for controlling said signals in accordance with the positions of the track switches, indication relays controlled by the track switches, a circuit network including a circuit conforming to each route through the track layout including contacts of said switch indication relays closed when the corresponding route is established and extending between contacts of the route relays for the signals at the opposite ends of such route, and means for energizing each exit lamp over a circuit in said network comprising connections to one terminal of a source of current over a front contact of a route relay at one end of said network and from the other terminal of said source through said lamp to a back contact of a route relay at the other end of said network.

Certificate of Correction

Patent No. 2,567,834

September 11, 1951

EARL M. ALLEN

It is hereby certified that error appears in the printed specification of the above numbered patent requiring correction as follows:

Column 10, line 75, for "lamps" read *lamp*; column 12, line 3, before "signal", second occurrence, insert *and*; line 36, after "indication" insert *lamp*; and that the said Letters Patent should be read as corrected above, so that the same may conform to the record of the case in the Patent Office.

Signed and sealed this 25th day of December, A. D. 1951.
